US00D881805S

(12) **United States Design Patent** (10) Patent No.: **US D881,805 S**
(45) Date of Patent: **** Apr. 21, 2020**

(54) **SOLAR MODULE**

(71) Applicant: **SOLYCO TECHNOLOGY GMBH**,
Berlin (DE)

(72) Inventor: **Lars Podlowski**, Berlin (DE)

(73) Assignee: **SOLYCO TECHNOLOGY GMBH**
(DE)

(**) Term: **15 Years**

(21) Appl. No.: **35/504,827**

(22) Filed: **Feb. 16, 2018**

(80) **Hague Agreement Data**

Int. Filing Date: **Feb. 16, 2018**

Int. Reg. No.: **DM/100794**

Int. Reg. Date: **Feb. 16, 2018**

Int. Reg. Pub. Date: **May 4, 2018**

(51) LOC (12) Cl. **13-02**

(52) U.S. Cl.

USPC **D13/102**

(58) **Field of Classification Search**

USPC **D13/102; D25/222**

CPC **H02S 20/23; F24S 25/50**

See application file for complete search history.

(74) Attorney, Agent, or Firm — Vorys, Sater, Seymour and Pease LLP

(57) **CLAIM**

The ornamental design for a solar module, as shown and described.

DESCRIPTION

1.1 is a left view;
1.2 is a front view;
1.3 is a back view;
1.4 is a front perspective view, which is identical to the back perspective view;
1.5 is a top view;
1.6 is a bottom view;
1.7 is a right view;
1.8 is a perspective view wherein a portion thereof is encircled with a broken line; and
1.9 is a detailed view of the portion encircled with the broken line in 1.8.
3.1 is a right view;
3.2 is a left view;
3.3 is a front view;
3.4 is a back view;
3.5 is a perspective view;
3.6 is a top view;
3.7 is a bottom view;
3.8 is a perspective view wherein a portion thereof is encircled with a broken line; and
3.9 is a detailed view of the portion encircled with the broken line in 3.8.

1 Claim, 18 Drawing Sheets
